UNITED STATES PATENT OFFICE

OLIVER A. OLSON, OF MINNEAPOLIS, MINNESOTA

RAILROAD SPIKE

Application filed December 31, 1927. Serial No. 243,864.

This invention relates to railroad spikes utilized for securing the rails to the ties.

It is the main object of my invention to provide a simple, highly improved railroad spike which may be manufactured at comparatively low cost which will efficiently secure the rail to the ties.

A further object is to provide a railroad spike which may be drawn inwardly against the flange of the rail when driven into the tie, and which will be prevented from upward displacement due to vibration of the rail or the yielding action of the tie, but which nevertheless may be easily removed when forcibly lifted a comparatively short distance by a suitable tool.

Another object of the invention is to provide a spike of the class above described which when driven into engagement with the flange of the rail will be locked in operative position, the structure of my spike drawing the head toward the flange of the rail when driven and moreover causing the stock of the tie to first compress and then expand to fill diminished portions in the shank.

These and other objects and advantages of the invention will be apparent from the following description made in connection with the accompanying drawings wherein like reference characters refer to similar parts throughout the several views and in which,

Fig. 1 is a vertical section taken through a tie and a rail, showing an embodiment of my improved spike securing the rail to said tie;

Fig. 2 is a front elevation of the embodiment of the invention shown in Fig. 1 detached;

Fig. 3 is a cross section taken on the line 3-3 of Fig. 2;

Fig. 4 is a side elevation of a slightly different form of the invention;

Fig. 5 is a plan view of the head of the same;

Fig. 6 is a front elevation of the same;

Fig. 7 is a cross section taken on the line 7-7 of Fig. 4.

In Fig. 1 an embodiment of my invention especially adapted for soft wood ties is shown applied to a rail R and a tie T. This spike

comprises an elongated shank 11 having at its upper end the usual enlarged head 12 provided at the front edge thereof with a claw adapted to engage the flange of the rail and having at its lower end a spear-shaped blade 55 portion 13 terminating in a wedge-shaped point 13^a adapted to be driven into the tie.

As shown in Fig. 3 the entire shank of my spike may be constructed from a bar or strip of material having a cross section of trapezoidal shape, leaving the spike with a longitudinal front edge narrower than its longitudinal rear edge. The purpose of this structure is to cause the spike to creep or wedge in toward the rail when it is driven into the tie 65 and while as shown in Figs. 1 to 3 the entire front edge is diminished a satisfactory spike may be formed with only a portion of the front longitudinal edge diminished.

The inclined edges forming the wedged-shaped point are disposed at different angles to the line of force L of the spike, the inclination of the front edge of the wedge being greater than that of the rear edge. This causes the lower end or point of the 75 spike to creep away from the rail as the spike is driven into the tie, resulting in bringing the upper end or head of the spike against the flange of the rail.

Intermediate of the head 12 and the blade 80 13 of my spike and on the front edge thereof I provide a bulge 14, the width of the shank diminishing or tapering from the bulge to the blade portion and consequently affording recessed portions adapted to be filled by 85 the expansion of the stock of the tie to securely hold the spike against displacement when driven to position. The diminished central portions of the shank may be defined at the rear longitudinal edge by an inclined 90 straight line 15 extending from the head 12 to the blade portion and may be defined at the forward longitudinal edge of the spike by a substantially straight line 16 extending 95 from the head 12 to the bulge 14 and approximately parallel with the line 15 and a straight line 17 inclined in the opposite direction to line 15 and extending from the bulge 14 to the blade portion 13. It will, of course, be 100 understood that the lines 15, 16 and 17 may

assume different shapes provided bulge 14 is left some distance below the head of the spike on the front longitudinal edge and provided a diminished portion is left between said bulge and said blade. The width of blade 13 is preferably somewhat less than the width of the upper portion of the shank above bulge 14.

The form of the invention illustrated in Figs. 4 to 7 inclusive is practically identical with the form previously described and similar parts and lines will be accordingly numbered the same. The only exception is that the stock of the shank is formed from a piece of material of substantially rectangular cross section and has the intermediate portions of its sides adjacent the forward edge and about the bulge recessed at 18 to afford a narrower forward edge than rear edge. In this form the shape of the shank formed by the lines 15, 16 and 17, the blade, the inclination of the wedge surfaces, the bulge 14, and the head 12 are identical with the form previously described.

The advantages and functions of my improved spike may be briefly summarized as follows:—

In driving my spike the point is disposed slightly outwardly of the longitudinal edge of the adjacent flange of the rail with the bulged or front longitudinal edge of the spike disposed toward the rail and the spike is driven vertically into the rail. The diminished width of the forward longitudinal edge of the spike causes the spike as it is driven to creep inwardly toward and against the flange of the rail. Moreover, as has been stated, the wedge-shaped point having wedging surfaces disposed at different angles causes the lower end of the spike to creep or be drawn outwardly thereby tilting or drawing the upper end of the spike inwardly snugly against the adjacent edge of the rail flange. If the spike is driven as above directed when fully set within the tie the bulge 14 will actually underlie the flange of the rail and the inclined edge defined by the line 16 will abut the longitudinal edge of the flange locking the spike against upward displacement until the spike has been forcibly raised by a suitable tool to bring bulge 14 above the flange.

In addition to the functions above described, when the spike is being driven into the rail the stock of the rail is first compressed by the spear shaped or diamond shaped blade 13 and then expands to fill the diminished portion directly above the said blade 13, thus additionally locking the spike to the tie. Since the upper portion of the shank is of greater width than the blade portion 13 the hole formed by the blade portion will always be snugly filled and there will be no play in the upper end of the shank.

Spikes heretofore widely used by railroads

have been generally unsatisfactory for the reason that they would soon work loose from the rail, endangering the safety of trains passing over the rails. Moreover, spikes heretofore used have had no means connected therewith for causing the shanks and head of the spike to be drawn inwardly against the flange of the rail when they are driven into the ties.

It will be apparent from the foregoing description that I have provided a simple, but highly efficient spike obviating the objections to spikes heretofore used and adapted to be manufactured at relatively low cost.

It will, of course, be understood that various changes may be made in the form, details, arrangement and proportions of the parts without departing from the scope of applicant's invention.

What is claimed is:—

1. In a railroad spike, a shank having substantially flat sides, a head, a blade portion at its lower end provided with a wedge-shaped entering point, the front and rear faces of the shank being sharply contracted to form shoulders at the upper termination of the blade portion, the rear face of the shank above the shoulder being defined by a plane rearwardly inclined to the axis of the spike, the forward face being defined by one plane portion parallel to the rear face extending downwardly from the head, and a second plane portion diverging upwardly from the forward shoulder and intersecting the above named plane portion to form a forward facing bulge. 90

2. In a railroad spike, a shank having substantially flat sides, a head, a blade portion at its lower end provided with a wedge-shaped entering point, the front and rear faces of the shank being sharply contracted to form shoulders at the upper termination of the blade portion, the rear face of the shank above the shoulder being inclined to the axis of the spike, the forward face above the shoulder having an upper portion substantially parallel to the rear face extending downwardly from the head, and a second portion diverging upwardly from the forward shoulder and intersecting the above named portion to form a forward facing bulge, said wedge-shaped entering point being defined by two intersecting planes, said planes extending at different angles to the axis of said spike. 115

In testimony whereof I affix my signature.
OLIVER A. OLSON.
